(57) **CLAIM**

The ornamental design for a water heater, as shown and described.

DESCRIPTION

FIG. 1 is a front, top and right side perspective view of a water heater, showing our new design;

FIG. 2 is a front, bottom and right side perspective view thereof;

FIG. 3 is a front view thereof;

FIG. 4 is a rear view thereof;

FIG. 5 is a right-side view thereof, the left side view being a mirror image of FIG. 5;

FIG. 6 is a top view thereof; and,

FIG. 7 is a bottom view thereof.

The parts shown in the broken lines do not form part of the claimed design.

1 Claim, 7 Drawing Sheets

FIG. 1

FIG. 2

FIG. 3

FIG. 4

FIG. 5

FIG. 6

FIG. 7
